7 Claims

ABSTRACT OF THE DISCLOSURE

A two-piece ventilated hat consisting of an optical frame provided with means on each of the collapsible temple bars thereof for detachably supporting a collapsible head cover. The supporting means includes a pair of rigid inverted U-shaped members which bridge the intermediate portions of the temple bars and thereby afford an increased rigidity with a minimum obstruction to the air circulation.

This invention relates to ventilated hats of the type disclosed in my prior Pat. No. 3,150,380, issued Sept. 29, 1964, but embodying a collapsible construction capable of affording maximum stability when in use and of occupying a minimum space for storage purposes when in nonuse.

Heretofore, various types of ventilated hats have been designed but have been found bulky, complex and unsuitable for handy storage (see Pat. No. 250,803). Other prior art hats have afforded a measure of collapsibility through the use of numerous separable parts which require considerable time and inconvenience to dismantle for storage and to erect for use.

It is therefore an object of this invention to provide a ventilated hat constructed and arranged to obviate the aforementioned objections. Briefly, the invention consists of a two-piece collapsible hat, namely, a collapsible optical or spectacle frame provided with specially constructed temple bars for detachably supporting a collapsible head cover.

It is another object of invention to provide a ventilated hat of the type described wherein each of the specially constructed temple bars is a trussed member including a rigid inverted U-shaped component having its legs extending upwardly from the bottom chord at spaced locations forwardly and rearwardly of the ear-supporting surface on the latter, whereby the upper horizontal leg-connecting portion of the U-shaped component will serve as the top chord of said trussed member.

Some of the objects of invention having been stated, other objects will appear as the description proceeds when taken in connection with the accompanying drawings, in which—

FIG. 1 is a side elevation of my ventilated hat as it appears when worn;

FIG. 1A is an enlarged sectional detail view taken along line 1A—1A in FIG. 1;

FIG. 2 is a top plan view of FIG. 1;

FIG. 3 is an enlarged sectional detail view taken along line 3—3 in FIG. 2;

FIG. 3A is an enlarged detail view of the lower left-hand portion of FIG. 3 showing a typical fastener for detachably securing the head cover to the optical frame;

FIG. 4 is a sectional detail view taken along line 4—4 in FIG. 2, showing a part of the head cover frame in collapsed position and omitting the covering material;

FIG. 5 is an isometric view of the optical frame of FIG. 1 in opened position and separate from the head cover;

FIG. 6 is an isometric view of the frame shown in FIG. 5 when in collapsed position, and

2

FIG. 7 is a schematic view showing the detached head cover in collapsed position.

Referring more specifically to the drawings, the numeral 10 denotes in dotted lines the silhouette of a person's head upon which is mounted a collapsible optical or spectacle frame assembly broadly designated by reference character 11, said frame comprising a nose rest or brow bar 12 and a pair of trussed or open-frame temple bar units 14 pivotally secured respectively to the opposite ends of the brow bar as at 15 and adapted to rest upon the wearer's ears. A collapsible head cover assembly broadly designated by numeral 17 is detachably secured upon the temple bar units 14, 14 by any suitable means such as snap fasteners, each of said fasteners consisting of a female component 19 on the temple bar unit 14 and a male component 19a on the cover assembly 17. Assemblies 11 and 17 will be explained more fully in the following description (FIGS. 2, 3, 3A, 5 and 6).

It will be observed in FIG. 5 that each of the temple bar units 14 comprises a bottom chord or ear bar 20 having an arcuate ear-bearing surface 21 on its lower edge, and a top chord 22 having integral with its opposite ends a pair of vertically disposed posts 23 and 24, the lower end of said posts being secured to the bottom chord 20 by means of screws 25 and 26 located on opposite sides of the ear-bearing surface 21. Additional holes 25a and 26a are provided in the lower end portions of posts 23 and 24 respectively, to thereby afford means for adjustment of the distance between the bottom and top chords, which adjustment will vary the vertical distance between the top of the wearer's head and the crown of the head cover.

Since the top chord 22 and end posts 23 and 24 consist of an inverted U-shaped one-piece member, the attachment of the lower ends of the posts to the lower chord 20 provides an exceptionally rigid temple bar unit capable of absorbing the stresses encountered during use of the hat. At the same time, the open-frame truss design affords openings 28 of maximum size through which air can freely pass as it circulates between the top of the wearer's head and the crown of the head cover assembly 17. Another important feature contributing to the rigidity and stability of the combined assemblies 11 and 17 is the relative positions of the post-connecting points 25 and 26 and the ear-bearing surface 21, said points being located forwardly and rearwardly of said surface.

In the event adjustment of the distance between the top and bottom chords of units should be unnecessary for a particular size of hats, the temple bar units 14 may each be cast from plastic, for example, and in one piece, thereby further contributing to simplicity of construction.

In the drawings, the members 20, 22, 23 and 24 of unit 14 are not necessarily drawn to scale since it is evident that the sizes of these members are preferably determined by the material used and the stresses carried. As shown, the top chord 22 and end posts would normally carry compressive stresses while the bottom chord is subjected to tensile stresses. Thus, the members 20, 22, 23 and 24 would be of a much smaller size than shown in the drawings if made from a light weight metal capable of carrying high unit compressive and tensile stresses.

It will be noted further in FIG. 5 that the proximate faces 24a of members or posts 24 are concave so as to approximately follow the contour of the wearer's head.

65 The collapsible head cover 17 is formed from a plurality of ribs 30 pivotally secured to vertically disposed crown pin 31 (FIGS. 2 and 3), said ribs having attached thereto a suitable cover sheet 32. A slide fastener 33 consisting of interengaging edge strips 33a and 33b is secured 70 between adjacent radially extending edges of the cover sheet 32 whereby the head cover may be collapsed.

When it is desired to collapse the combined assemblies 11 and 17, the snap fastener elements 19 and 19a are first separated, after which each assembly may be collapsed separately. The head cover assembly may be collapsed by separating fastener 33 and then rotating the ribs and attached cover sheet 32 about crown pin 31 to the collapsed position as shown in FIG. 7; and then confined in such position by suitable means such as an elastic band 39. Likewise, the optical frame may be collapsed to the position shown in FIG. 6 in a manner similar to the folding of a pair of spectacles. With assemblies 11 and 17 collapsed as shown and described, a minimum of space will be required for storage when not in use thus making it convenient to carry these assemblies in a small packet or a lady's purse.

In order to maintain the head cover assembly 17 in erect position during use, a suitable toggle strut is provided between adjacent ribs 30 (FIG. 1A), each strut comprising bars 35 and 36 pivotally secured to one another as at 37 and pivoted to the proximate sides of adjacent ribs as at 38. FIG. 4 shows the positions of bars 35 and 36 when the head cover assembly 17 is in a collapsed position such as shown in FIG. 7.

The combined assemblies 11 and 17 are removably held upon the wearer's head by suitable means such as flexible chin straps 40 and 41, said straps having the respective upper ends thereof secured to the temple bar bottom chords 20 as at 42 and the lower ends secured to one another by means such as snap fasteners 43.

I claim:

1. A ventilated hat comprising a spectacle frame having a horizontally disposed brow bar and a pair of rearwardly extendable temple bars pivotally secured to the opposite ends of said brow bar respectively, said temple bars being swingable inwardly from extended positions transversely of the brow bar to collapsed positions alongside the latter, an upwardly extending and rearwardly extendable support secured to and bridging the intermediate portion of each of said temple bars, said supports being inwardly swingable with their respective temple bars to

collapsed positions above said brow bar, a head cover, and means for detachably securing said head cover upon said bridging supports.

5 2. A ventilated hat as defined in claim 1 wherein said bridging supports each comprises an inverted U-shaped member.

10 3. A ventilated hat as defined in claim 2 and further comprising an arcuate ear-bearing surface on the lower edge of the free end of each of said temple bars, and wherein one leg of each U-shaped member is secured to its temple bar rearwardly of said ear-bearing surface.

15 4. A ventilated hat as defined in claim 3 wherein the proximate faces of the intermediate portions of said U-shaped supports are concave when the temple bars and supports are in rearwardly extending positions.

5 5. A ventilated hat as defined in claim 1 and further comprising means on the lower edge of each of the bridged intermediate temple bar portions for resting upon the wearer's ears.

20 6. A ventilated hat as defined in claim 1 wherein said head cover comprises a vertically disposed crown pin, and a plurality of radially disposed ribs each having one end pivotally mounted on said pin, said cover being separable along at least one path extending radially from said pin whereby the cover may be collapsed.

25 7. A ventilated hat as defined in claim 6 wherein said securing means consists of snap fasteners interconnecting said bridging supports and said ribs.
